UNITED STATES PATENT OFFICE

148,154

DESIGN FOR A PORTABLE COOKER

Marvin L. Failing, Los Angeles, Calif.

Application January 9, 1946, Serial No. 125,376

Term of patent 3½ years

(Cl. D81—10)

To all whom it may concern:

Be it known that I, Marvin L. Failing, a citizen of the United States of America and a resident of the city of Los Angeles, in the county of Los Angeles and state of California, have invented a new, original, and ornamental Design for Portable Cooker, of which the following is a specification, reference being had to the accompanying drawings, forming part thereof.

In the drawings:

Figure 1 is a perspective view of a portable cooker with the lid in partly open position, showing my new design.

Figure 2 is a perspective view taken from the opposite side of Figure 1.

The essential features of the design reside in the portions shown in full lines.

I claim:

The ornamental design for a portable cooker, substantially as shown and described.

MARVIN L. FAILING.
